UNITED STATES PATENT OFFICE.

JOSEPH JONES, ALFRED HARLEY, AND CHARLES H. FISHER, OF ALBANY,
NEW YORK.

IMPROVEMENT IN MECHANISMS FOR OPERATING RAILWAY TRANSFER-TABLES.

Specification forming part of Letters Patent No. 146,685, dated January 20, 1874; application filed
September 25, 1873.

To all whom it may concern:

Be it known that we, JOSEPH JONES, ALFRED HARLEY, and CHARLES H. FISHER, of Albany, Albany county, New York, have invented a new and Improved Transfer Apparatus for Railroads, &c., of which the following is a specification:

This invention consists in an apparatus for gradually overcoming the inertia of, and attaching cars, carriages, or other vehicles to, a cable or belt while the latter is in continuous motion, and for increasing the adhesion of the cable.

In the accompanying drawing, Figures 1, Sheet 1, show a plan view of the driving-wheels. Fig. 2, Sheet 1, shows a side view of the same. These views show the stationary driving-gearing with which our present invention is connected. Fig. 3, Sheet 2, is a plan, showing the arrangement of one side of the car or carriage, the other side being a duplicate in all its parts. Fig. 4, Sheet 2, is a side view of the same. Fig. 5, Sheet 2, is an end view. These figures, 3, 4, and 5, represent our present invention. Fig. 6, Sheet 3, is a general plan, showing the car or carriage, the relative position of the wheels, and the arrangement of the endless rope or cable.

A is the car or carriage, which is constructed in any desired form. B B represent the track on which the carriage runs. C is an endless rope, belt, or chain. E are driving-wheels, which are actuated from the engine. All these wheels are geared together and provided with pulleys, around which the endless rope or belt passes in the manner shown, and by which the slipping of the same is prevented, and the aggregate adhesion of the rope to all the wheels is secured. F represents a loose pulley or "idler," around which the endless rope or belt runs freely at the other extreme of the railway. The axis of said wheel or pulley revolves in a suitable longitudinal slide, and is provided with appliances for tightening the cable. G represents pulleys, of any desired number, having grooves in their peripheries to suit the form of the cable used. These pulleys are rigidly secured to the shafts H, which revolve in bearings attached to the

carriage A. I are spur-wheels, by which the shafts are geared together. On one of these shafts in each train, and opposite each other, a plane-faced brake-wheel, J, is rigidly secured, and furnished with friction clutch or brakes K, which are actuated by levers and connections L and M. O O are the carrying-wheels. P P are guide-wheels, which run on suitable axles, which allow them to be placed with their faces bearing against the sides of the rails, to retain the carriage in position on the track, instead of flanges. Q is a capstan, attached to one of the upright shafts H, said shafts being continued above the platform or floor of the car for that purpose. This capstan may be used as it is in case of a transfer-table for hauling the cars on and off the same. At both ends of each train, and directly under the cable, grooved pulleys are placed and revolved on suitable axles, for the purpose of guiding the rope upward and conducting it in a horizontal line into the groove of the rope-wheels.

The arrangement of the wheels, shafts, gearing, &c., on the other side is a duplicate in all its parts of the above, as shown in Sheet 3.

The operation is as follows: The cable is supposed to be in continuous motion, actuated by means of a belt on the pulley S, carrying the pulleys G, shafts H, gear-wheels I, and friction-wheel J around freely, while, at the same time, the carriage remains at rest; but when the brakes are applied to the friction-wheel J on one side of the endless cable, the brakes will allow the wheel J to slip, with constantly decreasing speed, until the inertia of the carriage is gradually overcome, when it will be held firmly, the whole train stopped, and the carriage will then move along at the same speed and in the same direction as that side of the cable on which the brakes are applied, while, at the same time, the pulleys and other attachments on the opposite side of the cable will continue to revolve freely. If the former are released and the brakes are in turn applied to the latter, the operation will be reversed, and the carriage will move in an opposite direction.

This is essentially a labor-saving apparatus,

the advantages of which will be readily understood and appreciated by railroad men.

Having thus described our invention, what we claim as new, and desire to secure by Letters Patent, is—

1. The endless belt C, around two or more wheels, E, geared together for the purpose of increasing the adhesion, substantially as and for the purpose described.

2. The belt C, passing partially around two or more pulleys, G, geared together, in com-

bination with a friction wheel or brake, K, substantially as and for the purpose described.

3. The capstan Q, in combination with one of the shafts H, as shown and described.

JOSEPH JONES.
ALFRED HARLEY.
CHAS. H. FISHER.
